ELECTRIC RAT GUARD

Filed April 6, 1931

W.E. O'Connell INVENTOR

BY A. L. Evans

ATTORNEY

WITNESS: *J. T. L. Wright*

UNITED STATES PATENT OFFICE

WALTER E. O'CONNELL, OF NEW ORLEANS, LOUISIANA

ELECTRIC RAT GUARD

Application filed April 6, 1931. Serial No. 528,175.

This invention relates to guards for ships' mooring lines or hawsers, and has for an object the provision of electrical means for preventing rodents from passing along the 5 hawsers from the dock to the ship when the latter is berthed.

Another object of the invention is the provision of a device of the above character which may be readily attached to and removed 10 from a hawser and connected with the ship's supply of current, so that rodents traveling along the hawser will receive sufficient current to cause their death.

With the above and other objects in view, 15 the invention further includes the following novel features and details of construction, to be hereinafter more fully described, illustrated in the accompanying drawings and pointed out in the appended claims.

20 In the drawings:—

Figure 1 is a side elevation of the invention shown applied to a section of a mooring line or hawser.

Figure 2 is a top plan view of the invention 25 per se, parts being broken away and shown in section.

Figure 3 is a bottom plan view with parts broken away and shown in section.

Figure 4 is a section on the line 4—4 of 30 Figure 1.

Figure 5 is a detail perspective view of the electrodes.

Figure 6 is a plan view of a ship with the invention applied to a mooring line.

35 Referring to the drawings in detail wherein like characters of reference denote corresponding parts, the invention as shown comprises a cuff which is made up of a pair of semi-circular sections 10 and 11. These sections are formed of suitable insulating material and are hingedly connected as shown at 12 by substantially semi-circular metallic plates 13, 14 and 15. These hinge plates extend around the sections 10 and 11 and are provided with protecting covers 16, 17 and 18 respectively, the cover 16 entirely inclosing the hinge plates 13, while the covers 17 and 18 are provided with openings 19 and 20 respectively which expose portions of the 45 plates or electrodes 14 and 15. The hinge 50

plates 13 and 14 are electrically connected as shown at 19, while the plates 13 and 15 are electrically connected by screws or similar conducting members 20 which extend through insulating posts 21 into a fuse box 22. The 55 fuse box 22 extends longitudinally of the cuff and is connected with opposite ends of the cuff by the posts 21. Conductor terminals 23 are secured upon the conducting members 20 within the fuse box, and these terminals are connected to conductor wires 24 and 25 which lead to a suitable source of current such as the ship's supply of current. The conductor 24 is connected to the terminal 23 of the electrode or hinge plates 60 13, while the conductor 25 is connected with the terminal of the electrode or hinge plates 15. Renewable fuses 26 are connected with in each of these conductors.

Secured to one of the sections of the cuff is 70 a strap 27 and hingedly secured to this strap as shown at 28 is a bolt 29 upon which is mounted a thumb nut 30. This bolt is adapted to enter a notch provided in a keeper 31 which is carried by the other cuff section so that 75 when the nut 23 is tightened to engage the keeper the cuff will be securely clamped upon the hawser. By this means the device may be readily attached to or removed from the 80 hawser.

A rodent traveling along the hawser will bridge the electrodes 14 and 15 so as to complete a circuit, whereupon the current traveling through the body of the rodent will electrocute said rodent and cause him to fall 85 from the hawser into the water.

The invention is susceptible of various changes in its form, proportions and minor details of construction and the right is herein reserved to make such changes as properly fall within the scope of the appended claims.

Having described the invention what is claimed is:—

1. In a rat guard, an insulated cuff comprising a pair of semi-circular members, means to connect said members, electrodes carried by the cuff, a protective casing for said electrodes, and means to connect said electrodes with a source of current. 95

2. In a rat guard, an insulated cuff com- 100

prising a pair of semi-circular members, means to connect said members, electrodes carried by the cuff, a fuse box connected to and extending longitudinally of the cuff, electric terminals located within the fuse box and electrically connected with the electrodes, conductors extending into the fuse box for connection with a source of current, and fuses located within the box and connected in said conductors.

10 3. In a rat guard, an insulated cuff comprising a pair of semi-circular members, means connecting said members to provide a sleeve, spaced split circular electrodes carried by the sleeve, and means to connect said electrodes with a source of current.

15 4. In a rat guard, an insulated cuff comprising a pair of semi-circular members, means connecting said members to provide a sleeve, spaced split circular electrodes carried by the sleeve, protective casings for said electrodes, certain of said protective casings having openings to expose portions of the electrodes, and means to connect said electrodes with a source of current.

20 5. In a rat guard, an insulated cuff comprising a pair of semi-circular members, sectional electrodes carried by said members and hingedly connected together to provide a hinge connection for said members, and means to connect the electrodes with a source of current.

25 In testimony whereof I affix my signature.
WALTER E. O'CONNELL.
